METHOD OF MAKING DRAWING DIES

Edgar W. Engle, Noroton, and Hershel Bryan Duncan, Stamford, Conn., assignors to Carboloy Company, Inc., Detroit, Mich., a corporation of New York

Application December 16, 1937, Serial No. 180,078

13 Claims. (Cl. 76—107)

The present invention relates to a method of making drawing dies utilizing the class of materials known in the trade as cemented hard metal carbides, such, for example, as the material described and claimed in the Schrotter Patent No. 1,549,615, issued August 11, 1925, consisting of minute particles of extremely hard tungsten carbide cemented together with a small amount of cobalt. Such materials are characterized by very great hardness, compressive strength and resistance to abrasion, but do not possess sufficient tensile strength to withstand the enormous forces set up in metal drawing operations such as the drawing of wire, rod, tubing and the like.

15 Drawing dies have heretofore been made by securing nibs of cemented carbide in casings of materials such as steel or bronze which possess high tensile strength and are so designed and made as to reinforce the cemented carbide nib.

20 In prior practice it has been necessary to prepare the casing by accurate machining and the nib by grinding and then to secure the latter within the former by brazing, or by shrink fitting, or by a forging operation as disclosed, for example, 25 in the patent to Morris Simons, No. 1,952,388, issued March 27, 1934.

A general object of the present invention is the provision of an effective method for making such dies which may be readily and cheaply practiced 30 in a minimum amount of time with a minimum amount of labor and material and which results in an efficient production of reenforced dies which are of simple construction and excellent quality, are capable of withstanding the enormous forces 35 set up in drawing operations, and have long lives.

A more specific object of the invention is the provision of an efficient method of providing such nibs with metal casings which grip the nibs and place them under unusually high compression, 40 eliminating the necessity of using supplemental drawing die holders, which method eliminates the necessity of preliminary annealing of casing material and many machining operations and 45 reduces to a minimum waste of material.

Other objects of the invention will in part be obvious and will in part appear hereinafter.

The invention accordingly comprises the several steps and the relation of one or more of such 50 steps with respect to each of the others thereof, which will be exemplified in the method herein-after disclosed, and the scope of the invention will be indicated in the claims.

For a fuller understanding of the nature and 55 objects of the invention reference should be had

to the following detailed description taken in connection with the accompanying drawing, in which:

Fig. 1 is a vertical sectional view of a forging die holder, associated structure and a blank or 5 slug of casing material showing a nib and forging plunger in position prior to a forging operation of the present invention;

Fig. 2 is a sectional view similar to Fig. 1 showing the nib forged into the casing blank or slug; 10

Fig. 3 is a similar sectional view showing the upper portion of the casing blank or slug forged over the upper end of the nib by a forging tool;

Fig. 4 is a vertical sectional view of a completed reenforced die; 15

Fig. 5 is a vertical sectional view similar to Figs. 2 and 3 with parts broken away, showing a modified structure for forging the nib into the casing blank or slug in accordance with a variation of the method of the invention; and

Fig. 6 is a vertical sectional view with parts broken away of the forging die holder and casing slug with a nib forged therein, showing a modified form of bottom plate used in the forging die holder.

By the present invention a cemented hard metal carbide nib is forced directly into a slug or flat blank of tool steel or other suitable material of high compressive strength, producing a drawing die of superior strength and eliminating to a large extent the machining and grinding operations and waste of high priced material which is characteristic of the practices heretofore followed.

The application of the present invention will be described with particular reference to the production of a wire drawing die having a nib of cemented tungsten carbide provided with a circular metal drawing passageway and surrounded by a casing of tool steel containing about .80% to 1.05% carbon, about .20% to .45% vanadium and, if desired, up to about .5% chromium, though it is to be understood that the invention is applicable to the production of drawing dies of other designs, with nibs or other materials of the same class, and with casings of other materials having the necessary properties of high elastic strength and thermal expansion.

Cylindrical bar stock of the selected tool steel in unannealed condition is cut by means of an 50 abrasive wheel cutting machine into sections of predetermined length, with substantially flat end faces. Each of these sections constitutes a casing slug or blank 10. Without further manipulation of any kind, each slug 10 is heated to a

suitable forging temperature between about 1850° F. and 2000° F. to make it plastic. It is then transferred quickly to a cup-shaped forging die 11, formed of hot forging steel such as chromium-tungsten steel or other suitable material, in a press of the type adapted to deliver percussive compression or a relatively slow hammer blow effect, such as a percussion, hydraulic or compression screw press. The forging die 11 preferably has the walls of the socket 12 therein tapered slightly and is provided with an ejection passage 13 in the bottom thereof to permit ready removal of a completed die assembly. A bottom plate 14, preferably formed of similar metallic material, is seated in the bottom of the socket 12.

A cemented tungsten carbide nib 15, without any preliminary finishing being required, is centered on top of the hot slug 10 and the press is operated to cause a press plunger 16 to drive or force the nib 15 into the slug 10 to the desired depth causing the nib to displace the slug material, preferably to an extent so that a portion thereof 17 projects above the upper end of the nib as shown in Fig. 2. Preferably the operation of the press is such that simultaneously or sequentially projecting portion 17 of the slug material is caused to flow over the outer portion of the upper end of the nib 15 as shown in Fig. 3.

The encased nib is then ejected from the forging die 11, allowed to cool to about 800° F. and thereafter tempered at about 900° F. to 1250° F., preferably about 1150° F., to develop the proper properties in the casing steel. After the tempering is complete, the casing material at the center of the bottom of the die is removed by a simple trepanning tool to form an opening 18. All that is necessary to finish the tool is to make and/or finish a wire-drawing hole 19 in the nib 15, to machine the outer surface 20 of the casing to insure concentricity with the hole 19 and, if desired, machine out opening 21 in the casing communicating with the wire-drawing hole.

If desired, although not necessary, the nib may have its surfaces ground and/or sand blasted to remove surface defects or adhesions prior to being forced into the casing slug and may be preheated. The nib forced into the casing slug may be a blank nib or a cored nib, i. e. a nib provided with a wire-drawing hole. If a blank nib is used, it is preferably provided with a center 22 prior to being forced into the casing slug to permit ready machining of the circumferential face of the casing concentric with the axis of the nib and to facilitate opening up the bottom 55 of the casing. A bottom plate 23 provided with a suitable boss 24, frusto-conical in shape, may be used in the forging die 11 so that during forging an indentation will be formed in the bottom of the casing slug, as shown in Fig. 6. A similar indentation may be machined or formed in the bottom face of the slug prior to the forging whereby such a bottom plate may be advantageously used to aid in centering the slug in the forging die.

65 The nib 15 may be centered on the hot slug 10 and suitably guided during forcing operation by a pair of centering tongs or by a centering ring 25 seated within the socket 12 on the top of the hot slug 10. The portion of the casing material 70 17 which projects above the upper end of the nib 15 may be forged over the outer portion of the upper end of the nib in a variety of ways. In accordance with one method suggested in Fig. 3, the plunger 16 is retracted and a forging plate 75 26 is substituted for the centering ring 25. The

forging plate 26 preferably is provided with a flat lower face and shaped to be received within the socket 12. A flange 27 may limit the downward movement thereof. The lower face of the plate 26 is preferably provided with a circular boss 28 having a circumferential face curved smoothly to merge with the flat lower face to cause the projecting portion 17 of the casing material to flow over the outer portion of the upper end of the nib 15 and provide the opening 21 when compressive force is applied to the forging plate by the plunger 16 engaging in a recess 29 in the upper face thereof.

As an alternative method of forging the projecting portion 17 of the casing material over the outer portion of the upper end of the nib 15, the centering ring 25 may be omitted and the plunger 16 provided with an abutment located a suitable distance above the engaging end thereof so that as the nib is forced into the slug 10 the abutment causes the projecting portion 17 to flow inwardly over the outer portion of the upper end of the nib. Further alternatives are suggested in Fig. 5 by arrows, which may consist in restraining upward movement of the centering ring 25 caused by upward movement of the projecting portion 17 as the nib displaces slug material or the application of compressive force to the guide ring after it has been raised to a position similar to that shown in Fig. 2. A modified form of 30 plunger 30 may be used, the plunger being provided with a reduced end 31 shaped similarly to the boss 28 on the forging plate 26 in order similarly to shape the projecting portion 17 and the passage 21.

35 Materials other than tool steel may be used for the casing. Such materials should have high tensile strength and higher coefficient of thermal expansion than the nib material. Various types of bronze, such as aluminum bronze known as 40 "Avialite," satisfy these requirements. A suitable forging temperature for bronze is about 1500° F.

The casing slug may be heated to the forging temperature in a period of minutes. The slug 10 at the forging temperature should fit easily 45 into the socket 12 of the forging die 11 which preferably is cold when the heated slug is placed therein. Consequent chilling of the surface of the slug eliminates any tendency for it to weld to the socket face of the forging die.

50 By the present invention the manufacture of cemented carbide drawing dies is greatly simplified and the expense materially reduced. For example, the steel bar stock can be used in the unannealed condition, thus eliminating the expense of annealing which has heretofore been necessary. Preliminary machining of the casing material is entirely eliminated. Waste of the steel is eliminated with the exception of a very small amount which is trimmed from the casing 55 after the forging operation is completed. The preliminary grinding of the cemented tungsten carbide nib heretofore necessary to fit the nib to the machined casing is entirely eliminated. The amount of final grinding of the casing to insure its concentricity with the hole in the nib 60 is reduced to a minimum.

65 In addition to the elimination of machining and grinding operations heretofore necessary and the elimination of waste, the present invention makes possible the production of drawing dies of superior strength and decreased liability to breakage in service.

70 As illustrative of the compression under which a nib is placed by the casing formed in accordance 75

with the present invention in order to reenforce the nib against enormous forces set up by the drawing operations and thereby avoid likelihood of cracking the nib, the following test was carried out. A nib was forged into a steel casing in the manner described. Both ends of the casing were cut off to expose the full diameter of the nib. The assembly was then heated to 600° F. and mounted in an arbor press. It was impossible for two men to push the nib out of the casing with the press. The assembly was then heated to 900° F., replaced in the arbor press and two men succeeded in pushing the nib half way out of the casing but after the assembly had cooled off it was impossible for them to push the nib further out of the casing.

In the claims the use of the terms "hard metallic nib" and "blank slug of casing material" are used respectively to identify hard metallic material having low tensile strength, great hardness, high melting point and low coefficient of thermal expansion, such as a cemented hard metal carbide; and a block or substantially solid piece of metallic casing material which is deformable and has high tensile strength and a higher coefficient of thermal expansion than the nib material so that it will have high shrinkage characteristics and which has not been provided preliminarily with a substantial recess or cavity for reception of a nib.

It will thus be seen that the objects set forth above are attained by the present invention in an efficient manner. Since certain changes may be made in carrying out the above method without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described our invention, what we claim as new and desire to secure by Letters Patent, is:

1. The method of making a drawing die, comprising heating a blank slug of casing material to a forging temperature, forcing a hard metallic nib into said slug by compressive force to displace casing material while limiting lateral expansion thereof causing casing material to project above the upper end of said nib, and hot-forging the projecting portion of the casing material over the upper end of said nib.

2. The method of making a drawing die, comprising heating a blank slug of casing material to a forging temperature, forcing a hard metallic nib into said slug by compressive force to displace casing material while limiting lateral expansion thereof causing casing material to project above the upper end of said nib, hot-forging the projecting portion of the casing material over the upper end of said nib, and heat treating the resulting assembly to cause the casing material to place said nib under high compression.

3. The method of making a drawing die, comprising heating a blank slug of casing material to a forging temperature, placing the hot slug in a forging die for limiting lateral expansion of said slug during forging, centering a hard metallic nib upon said hot slug, forcing said nib completely into said slug by compressive force to thereby displace casing material until it extends

above said nib and forms a casing around said nib while preventing axial downward movement of said casing material and thereafter ejecting the encased nib from said forging die.

4. The method of making a drawing die, comprising heating a blank slug of casing material to a forging temperature, placing the hot slug in a forging die for limiting lateral expansion of said slug, centering a hard metallic nib upon said hot slug, forcing said nib into said slug by compressive force to displace casing material causing it to project above the upper end of said nib, and hot-forging the projecting portion of the casing material over the upper end of said nib.

5. The method of making a drawing die, comprising heating a blank slug of casing material to a forging temperature, placing the hot slug in a forging die for limiting lateral expansion of said slug, centering a hard metallic nib upon said hot slug, forcing said nib into said slug by compressive force to displace casing material causing it to project above the upper end of said nib, hot-forging the projecting portion of the casing material over the upper end of said nib, and heat treating the resulting assembly to cause the casing material to place said nib under high compression.

6. The method of making a drawing die, comprising heating a blank slug of casing material to a forging temperature, placing the hot slug in a forging die for limiting lateral expansion of said slug, centering a hard metallic nib upon said hot slug, said nib having a lower coefficient of expansion than said slug, forcing said nib completely into said slug by compressive force to displace casing material so that the entire sides of said nib are surrounded by said casing material, guiding said nib during the said forcing operation, preventing axial downward movement of said casing material and thereafter ejecting the encased nib from said forging die.

7. The method of making a drawing die, comprising heating a blank slug of casing material to a forging temperature, placing the hot slug in a forging die for limiting lateral expansion of said slug, positioning above said slug a nib-centering member having a guideway, placing a hard metallic nib in the guideway, forcing said nib into said slug by compressive force to displace casing material causing it to project above the upper end of said nib, and hot-forging the projecting portion of the casing material over the upper end of said nib.

8. The method of making a drawing die, comprising heating a cylindrical blank slug of casing material to a forging temperature, placing the hot slug in a circular socket of a forging die adapted to limit lateral expansion of said slug, positioning a nib-centering guide ring of substantial thickness in the forging die socket above said slug, placing a nib of hard metallic material in said ring, forcing said nib into said slug by compressive force to displace casing material causing it to project above the upper end of said nib, and hot-forging the projecting portion of the casing material over the upper end of said nib.

9. The method of making a drawing die, comprising heating a cylindrical blank slug of casing material to a forging temperature, placing the hot slug in a circular socket of a forging die adapted to limit lateral expansion of said slug, positioning a nib-centering guide ring of substantial thickness in the forging die socket above said slug, placing a nib of hard metallic material in said ring, forcing said nib into said slug by compressive force to displace casing material causing

it to project above the upper end of said nib, and utilizing said ring in cooperation with means for forcing said nib into said slug whereby the bottom face of said ring causes casing material to flow over the upper end of said nib.

- 5 10. The method of making a drawing die, comprising heating a cylindrical blank slug of casing material to a forging temperature, placing the hot slug in a circular socket of a forging die adapted 10 to limit lateral expansion of said slug, positioning a nib-centering guide ring of substantial thickness in the forging die socket above said slug, placing a nib of hard metallic material in said ring, forcing said nib into said slug by compressive force to displace casing material causing 15 it to project above the upper end of said nib, and restraining the upward movement of said ring to cause the casing material to flow over the upper end of said nib.
- 20 11. The method of making a drawing die, comprising heating a blank slug of steel casing material to a temperature between about 1850° F. and 2000° F., forcing a cemented hard metal carbide nib into said casing blank by compressive 25 force to displace casing steel while limiting lateral expansion thereof so that the sides of said nib are surrounded by casing material, and cooling the steel to and maintaining it at about 800° F. until it shrinks to place said nib under high 30 compression.

12. The method of making a drawing die, comprising

prising heating a blank slug of steel casing material of high compressive strength to a temperature between about 1850° F. and 2000° F., placing the hot slug in a forging die for limiting lateral expansion of said slug during forging, centering 5 a cemented hard metal carbide nib upon said hot slug, hot-forging said nib into said slug by compressive force to displace casing steel causing it to project above the upper end of said nib, hot-forging the projecting portion of the casing steel 10 over the upper end of said nib, heat treating the resultant steel casing at about 800° F. to place said nib under high compression, and tempering the resultant die at a temperature between about 900° F. and 1250° F.

15 13. The method of making a drawing die, comprising heating a blank slug of casing material to a forging temperature, placing the hot slug in a forging die for limiting lateral expansion of 20 said slug, holding a hard, metallic nib substantially centered upon said slug by means permitting longitudinal movement of said nib while forcing said nib into said slug, forcing said nib completely into said slug by compressive force to thereby displace said casing material until it extends well 25 above said nib while preventing axial downward movement of said casing material and thereafter ejecting the encased nib from said forging die.
